UNITED STATES PATENT OFFICE

2,443,283

WOODEN TUMBLING BARREL

Joseph N. Wallace, Westville, Conn.

Application October 30, 1946, Serial No. 706,763

7 Claims. (Cl. 51—164)

1

The present invention relates to novel and useful improvements in a tumbling barrel and more specifically pertains to an improved construction of such a device which is particularly adapted for long life in industrial use.

The principal objects of the invention reside in providing a tumbling barrel which is particularly adapted for inexpensive construction, extremely long life and ready construction from plentiful material, for tumbling and shaking together a plurality of industrial objects such as small castings or the like for polishing and cleaning the same.

Additional objects of the invention envision the construction of a tumbling barrel which may be satisfactorily constructed or fashioned from small wooden blocks into a rigid, durable and reliable construction; wherein novel means are provided for assembling the wooden blocks into staves and then uniting these staves into a barrel; wherein improved means are provided for maintaining and reinforcing the staves in their assembled position; wherein novel door means are provided for obtaining access to the interior of the device; wherein efficient sealing means are provided for insuring a leak-proof opening about the door panel of the device; and wherein novel means are provided for supporting the barrel for axial rotation in accordance with conventional usage of this art.

These, together with various ancillary objects of the invention are obtained by the apparatus set forth in the accompanying drawings, wherein:

Figure 1 is an elevational view illustrating the manner of mounting and operating a rotating barrel in accordance with this invention;

Figure 2 is an end elevational view of the barrel being taken substantially upon the line 2—2 of Figure 1;

Figure 3 is a transverse vertical sectional view being taken substantially upon the line 3—3 of Figure 1;

Figure 4 is a fragmentary detailed view in vertical section being taken substantially upon the line 4—4 of Figure 2; and,

Figure 5 is a detailed view, similar to Figure 3, but showing a modified fastening means for the cover of the device.

Referring now more specifically to the accompanying drawings, wherein like numerals indicate similar parts throughout the several views, 10 denotes generally the tumbling barrel forming the subject matter of this invention, which as shown, is rotatably supported upon a pair of standards 12 of any suitable construction, and is conveniently driven by means of a belt 14 or the like, from a driving pulley 16 mounted on a rotating driving shaft 18, this being a known and conventional form of driving means for

5

tumbling barrels. As shown in Figure 1, it is contemplated that a plurality of barrels 10 may be disposed in end-to-end axial alignment, with their supporting axles journaled for rotation in common bearing boxes 20 carried by the upper end of the standards 12, it being understood that a single bearing box will accommodate in end-to-end alignment the co-axial supporting axles of a pair of adjacent barrels 10.

In accordance with the dictates of this invention, as shown best in Figures 1, 2 and 4, the barrel is formed by a pair of preferably cast-iron end plates 22 of any suitable configuration, it being noted that in the form chosen for purposes of illustration of the principles of the invention, the end plates are depicted as octagonal in shape. The pair of end plates are provided with axially extending shafts 24 constituting axles for supporting the barrel, these shafts being journaled in the bearing boxes. Each of the end plates 22 is further provided with laterally extending flanges 26 which form a periphery which as shown in Figure 2, is octagonal in shape, although as above mentioned, these flanges may define an external surface of any desired or suitable contour.

As shown more clearly in Figure 2, the end plates 22 are enclosed about their peripheral surface upon the flanges 26, with a plurality of wooden staves 28, and a further stave 30 constituting a door for a purpose to be subsequently set forth. As will readily be seen by reference to Figure 4, each of the staves 28 is formed by a plurality of wooden blocks 32 disposed in side-by-side relation and preferably secured to each other as by gluing under pressure or the like, and being further rigidly united by a pair of longitudinally extending reinforcing members 34, preferably in the form of steel bars or the like which are recessed in longitudinal grooves 36, likewise extending the full length of the staves 28. Suitable bolts and nuts 38 are provided for detachably securing the staves to the lateral flanges 26 of the end plates 22.

I desire at this point, to call particular attention to the fact that the original wooden blocks 32 are so disposed, that the grain therein extends radially outward from the center of rotation of the barrel, whereby all the wear taken by the inner surfaces of the blocks, will be upon the ends of the grain of the blocks, thereby vastly increasing the life thereof. It has been found by experiment that when the blocks are so disposed, their life is thirty to thirty-five times as long as when they are disposed with the wear occurring lengthwise of the grain of the wood.

In order to provide greater rigidity between the adjacent staves, there is provided a keying or a splined connection between the conterminous edges of seven of the staves forming the

body of the barrel. This construction is shown clearly in Figure 3, wherein it will be noted that the edges of each of the staves is cut at a suitable angle relative to the flat inner and outer surfaces thereof, in order that the staves may be smoothly and snugly joined to form an octagonal shaped barrel, and longitudinally extending flat strips 38 of wood or any other suitable material are imbedded in complementary grooves or channels 38 recessed into the conterminous edges of said staves. It will thus be seen that each of the staves 28 is rigidly attached by a key or spline throughout its entire length with an adjacent stave, thereby providing an extremely and durable device for the purpose intended.

Attention is now directed more particularly to Figures 1 and 3 showing the construction and mode of attachment of the staves forming the door 30 of the device. This stave 30 is secured by suitable hinges 42 to one of the adjoining staves 28, and is provided with a hasp or other suitable locking means 44 for engagement with the other adjoining stave 28, in order to fasten or secure the door in place. In order to reinforce the contiguous edges of the staves 28 which abut upon the door 30, a strip 46, similar to the above mentioned splines 38, is secured in a longitudinally extending groove 48 in the edge of each of the adjacent stave members 28, it being noted that the outer edge of the strip 46 is disposed flush with the edge of the staves 28. This strip serves to reinforce and key together the plurality of parallelly disposed individual blocks 32. A pair of similar keys 46 are provided in the juxtaposed edges of the cover 30 for a similar purpose, while a further reinforcing member in the form of a strip 50 is provided at the outer surface and edges of the cover 30, to form a reinforcement and prevent splitting or fracturing of the wooden blocks at this point of wear.

From the foregoing, it will be readily seen that the hasp 44 may be released and the cover 30 opened at its hinges 42, whereupon access may be had to the interior of the barrel 10 for the purpose of charging the same with articles to be treated or removing finished articles therefrom. Preferably, a suitable sealing means is provided for further making a tight fit between the cover and the adjacent stave 28, and this sealing means may conveniently take the form of a felt strip 52 or the like secured to the adjacent edges of the staves 28 for juxtaposition to the edges of the cover 30.

Attention is next directed to the modified form of construction shown in Figure 5, wherein it will be seen that the cover member 30, which is of identical construction with that previously described, may be provided with detachable fastening means such as the wing nuts and bolts 54 for attaching the same to the flanges 26 of the end plates 22, the construction being otherwise identical with that previously set forth.

Since numerous modifications, falling within the scope of the principles of this invention will readily be clear to those skilled in this art, the invention is not to be limited except in accordance with the scope of the appended claims.

What is claimed as new is:

1. A tumbling barrel consisting of a plurality of wooden staves joined edgewise and disposed in parallel relation about a longitudinal axis, means supporting said barrel for rotation upon said longitudinal axis, said staves being assembled with the end grain of the wood radially disposed

relative to the center of rotation of the barrel, and means for rotating said barrel, said staves being each composed of a plurality of blocks secured in sidewise alignment and a plurality of reinforcing means extending longitudinally of each stave and embedded in longitudinally extending external grooves therein.

2. The combination of claim 1 wherein said staves are secured upon peripheral flanges of ends of said barrel.

3. A tumbling barrel consisting of a plurality of wooden staves joined edgewise and disposed in parallel relation about a longitudinal axis, means supporting said barrel for rotating upon said longitudinal axis, said staves being assembled with the end grain of the wood radially disposed relative to the center of rotation of the barrel, and means for rotating said barrel, one of said staves being removable to constitute a door for said barrel, and reinforcing strips extending longitudinally of each edge of said door and recessed flush with the surface thereof.

4. A tumbling barrel consisting of a plurality of wooden staves joined edgewise and disposed in parallel relation about a longitudinal axis, means supporting said barrel for rotation upon said longitudinal axis, said staves being assembled with the end grain of the wood radially disposed relative to the center of rotation of the barrel, means for rotating said barrel, each of said staves being secured to the adjacent stave by a longitudinally extending spline seating in complementary grooves in conterminous edges of said staves and extending the length thereof.

5. A tumbling barrel including a plurality of wooden staves joined edgewise, each of said staves consisting of a plurality of blocks in sidewise alignment and having reinforcing and tying means extending through each block and longitudinally of each stave, longitudinally extending reinforcing strips secured to the exterior surface of said staves.

6. A tumbling barrel including a plurality of staves joined edgewise, each of said staves consisting of a plurality of blocks in sidewise alignment and having reinforcing and tying means extending through each block and longitudinally of each stave, said reinforcing strips being seated in longitudinal external grooves in said staves.

7. A tumbling barrel including a plurality of wooden staves joined edgewise, each of said staves consisting of a plurality of blocks in sidewise alignment and having reinforcing and tying means extending through each block and longitudinally of each stave, a longitudinally extending fastening key engaging the conterminous edges of adjacent staves throughout their length.
